The ornamental design for a magnetic resonance imaging system, as shown and described.

DESCRIPTION

FIG. 1 is a front, left perspective view of a magnetic resonance imaging system, showing our new design;
FIG. 2 is a rear, right perspective view thereof;
FIG. 3 is a rear, left, top perspective view thereof;
FIG. 4 is a front elevational view thereof;
FIG. 5 is a rear elevational view thereof;
FIG. 6 is a top plan view thereof, on a smaller scale;
FIG. 7 is a right elevational view thereof, on a smaller scale; and,
FIG. 8 is left elevational view thereof.
